(57) **CLAIM**

(21) Appl. No.: **29/217,438**

An ornamental design for a sprue bush for a disc-molding die, as shown and described.

(22) Filed: **Nov. 17, 2004**

DESCRIPTION

(51) **LOC (8) Cl.** **15-09**

FIG. 1 is a perspective view of a sprue bush for a disc-

(52) **U.S. Cl.** **D15/135**

molding die;

(58) **Field of Classification Search** D15/135-137;

FIG. 2 is a front view thereof;

425/226, 547, 574; 264/328.11, 39

FIG. 3 is a rear view thereof;

See application file for complete search history.

FIG. 4 is a left side view thereof;

425/226, 547, 574; 264/328.11, 39

FIG. 5 is a right side view thereof;

425/226, 547, 574; 264/328.11, 39

FIG. 6 is a top plan view thereof; and,

425/226, 547, 574; 264/328.11, 39

FIG. 7 is a bottom view thereof.

425/226, 547, 574; 264/328.11, 39

The broken lines shown in the bottom view are for illustrative purpose only and form no part of the claimed design.
